US00D797350S

(12) **United States Design Patent** (10) Patent No.: **US D797,350 S**
 Reynolds (45) Date of Patent: ** Sep. 12, 2017

(54) **LIGHT FIXTURE**(71) Applicant: **IP Holdings, LLC**, Vancouver, WA (US)(72) Inventor: **Christopher Reynolds**, Vancouver, WA (US)(73) Assignee: **IP Holdings, LLC**, Vancouver, WA (US)(**) Term: **15 Years**(21) Appl. No.: **29/583,006**(22) Filed: **Nov. 1, 2016**(51) LOC (10) Cl. **26-05**

(52) U.S. Cl.

USPC ..... **D26/118**(58) **Field of Classification Search**

CLAIM

The ornamental design for a light fixture, as shown and described.

DESCRIPTION

FIG. 1 is a perspective view of a light fixture, as viewed from below, showing my new design;

FIG. 2 is a perspective view of the light fixture shown in FIG. 1, as viewed from above;

FIG. 3 is a left side view of the light fixture shown in FIG. 1;

FIG. 4 is a right side view of the light fixture shown in FIG. 1;

FIG. 5 is a front elevation view of the light fixture shown in FIG. 1;

FIG. 6 is a rear elevation view of the light fixture shown in FIG. 1;

FIG. 7 is a bottom plan view of the light fixture shown in FIG. 1; and,

FIG. 8 is a top plan view of the light fixture shown in FIG. 1.

The broken-line disclosure shown in the views is understood to represent portions of the article in which the claimed design is embodied, but which form no part of the claimed design.
